UNITED STATES PATENT OFFICE.

ARTHUR H. PATTERSON, OF FORT COLLINS, COLORADO, ASSIGNOR OF
TWO-THIRDS TO ELIAS D. ROTH, OF SAME PLACE, AND WILLIAM F.
CODY, OF NORTH PLATTE, NEBRASKA.

WEIGHING ATTACHMENT FOR WAGONS.

SPECIFICATION forming part of Letters Patent No. 357,854, dated February 15, 1887.

Application filed July 19, 1886. Serial No. 208,449. (No model.)

To all whom it may concern:

Be it known that I, ARTHUR H. PATTERSON, a citizen of the United States, residing at Fort Collins, in the county of Larimer and State of Colorado, have invented certain new and useful Improvements in Weighing Attachments for Vehicles, of which the following is a specification, reference being had therein to the accompanying drawings.

10 My invention relates to self-weighing wagons, its object being to provide means connected to the frame of a vehicle which, when loads are placed thereon, will indicate upon a suitable scale and by a suitable pointer the 15 number of pounds the vehicle is carrying, as will be hereinafter more fully set forth.

In the accompanying drawings, making part of this specification, Figure 1 represents a longitudinal section; Fig. 2, a cross-section; Fig. 20 3, a detail view of the fulcrum-bearing of the side levers; Fig. 4, a vertical sectional view of the same, and Fig. 5 a detail view of one of the clutches upon the outer ends of the side levers.

25 In the figures, A A represent the wheels of the vehicle which support the axles C C, and which are connected by the reach B.

D D represent two levers at each side of the running-gear, which are pivoted together at 30 their inner ends by means of a rod, E. These levers are provided at their outer ends with clutches I I. The forward clutches fit over the bolster on the front axle and are provided with anti-friction rollers i i, as represented. 35 The rear clutches fit either over the rear axle or over a bar on the same.

Projecting upward from the bar E are two rods, e e, which are surrounded with coiled-wire springs d. These springs d d are 40 mounted with the flanged caps a a, to which is connected a pointer, x. By the side of this pointer is a graduated index-plate, K. As

the pointer rises or falls the plate indicates the number of pounds on the vehicle.

F represents a metallic frame, which is provided with the standards H H.

G G represent plates which are secured to the upper sides of the levers D D. These plates have upwardly-projecting prongs, which embrace the sides of the iron frame F. Secured in the faces of the plates G G are steel or case-hardened bearing-pieces m m.

To the under side of the frame F are secured plates which have depending V-shaped bearing-pieces L, which rest upon the pieces m m. 55 The point of contact of the bearing here is so small that there will be little or no friction.

The body of the vehicle can rest upon the metallic frame F. The springs and indicating-plate may be either upon the inside or outside 60 of the body, but preferably on the outside.

I may use no body at all, but simply place the load upon the frame F.

Having thus fully described my invention, what I claim as new, and desire to secure by 65 Letters Patent, is—

1. The levers D D, hinged together at their inner ends, in combination with rods e e, springs d d, caps a a, bearing a pointer, and the indicating-plate K, the several parts being 70 connected to the running-gear of a wagon, substantially as and for the purpose set forth.

2. The combination, with the frame F and the bearings L, of the levers D, connected together at their inner ends, the rods e, springs 75 d, caps a, bearings G, clutches I, and the vehicle running-gear and indicating devices, substantially as described.

In testimony whereof I affix my signature in presence of two witnesses.

ARTHUR H. PATTERSON.
